CLAIM

The ornamental design for an electrical connector, as shown and described.

DESCRIPTION

FIG. 1 is a perspective view of an electrical connector embodying our design and shown in a closed position; FIG. 2 is a perspective view of an electrical connector embodying our design and shown in a slightly separated position;

FIG. 3 is a perspective view of an electrical connector embodying our design and shown in a fully separated position; and,

FIG. 4 is an underside view of an electrical connector embodying our design.

The rear and left side of the electrical connector are the same as the front and right side respectively.
